DESIGN FOR A BOOTEE

William A. Clark, St. Louis, Mo., assignor to W. L.
M. Clark, Inc., St. Louis, Mo., a corporation of Missouri

Application November 30, 1942, Serial No. 108,913

Term of patent 7 years

To all whom it may concern:

Be it known that I, William A. Clark, a citizen of the United States, residing in the city of St. Louis and State of Missouri, have invented a new, original, and ornamental Design for a Bootee, of which the following is a specification, reference being had to the accompanying drawing forming part thereof. The figure is a perspective view of a bootie, showing my new design, the opposite side presenting substantially the same appearance as the side shown.

I claim:

The ornamental design for a bootie, substantially as shown and described.

WILLIAM A. CLARK.
